(57) **CLAIM**

We claim the ornamental design for a tap collar, as shown and described.

DESCRIPTION

FIG. 1 is a front perspective view of a tap collar according to an embodiment of the present invention;

FIG. 2 is a fragmentary exploded perspective view of the bottom of the tap collar of FIG. 1;

FIG. 3 is a rear view of the tap collar of FIG. 1;

FIG. 4 is a front view of a tap collar with an attached strap according to an embodiment of the present invention;

FIG. 5 is a fragmentary perspective view of the bottom of the tap collar and strap of FIG. 4;

FIG. 6 is a rear view of the tap collar and strap of FIG. 4; and, FIG. 7 is a view of the tap collar and strap of FIG. 4 attached to a bar tap.

The broken line(s) shown in the drawings are for illustrative purposes only and form no part of the claimed design.

The shading lines shown in the drawing(s) represent the approximate three-dimensional contour of the design, and are not intended to indicate surface decoration.

Portions of the tap collar that are not shown in the drawing(s) form no part of the claimed design.
